His Attorney.

UNITED STATES PATENT OFFICE.

EDWARD A. EVERETT, OF NEW YORK, N. Y., ASSIGNOR TO Q & C COMPANY, OF NEW YORK, N. Y., A CORPORATION OF MAINE.

ELECTRIC HEATER FOR OUTDOOR USE.

1,408,183.

Specification of Letters Patent. Patented Feb. 28, 1922.

Application filed March 13, 1919. Serial No. 282,423.

To all whom it may concern:

Be it known that I, EDWARD A. EVERETT, a citizen of the United States, and resident of New York, in the county of New York and State of New York, have invented certain new and useful Improvements in Electric Heaters for Outdoor Use, of which the following is a specification.

This invention relates to electric heaters and has for an object providing a heater suitable for out-door service that is rugged, that can stand excessive vibration and knocks such as would be encountered on a railroad track and that is effective when immersed in water. In the accompanying drawings forming part of this specification, Fig. 1, shows a heater unit complete, Fig. 2, is a sectional elevation with part of the coil, however, shown complete, Fig. 3 is a cross-section on line *a*—*b* of Fig. 2; Fig. 4 is a section of the safety valve and Figs. 5 and 6 show the application of the heater units to a railroad switch.

11 represents a length of wrought iron pipe to which the reducing caps 12 and 13 are screwed. Into the cap 12 the pipe 14 is screwed and into the cap 13 the pipe 15 carrying the valve 16 is screwed, however, this valve may be screwed directly into cap 13. Pipe 29 is screwed into cap 12 and extends within pipe 11 between caps 12 and 13. This pipe is covered with a layer of asbestos cloth 28, Fig. 3 which is a non-conductor of heat and also forms a cushion to take up small vibrations from the outer covering and heating coil. The outer covering 27 consists of a cement applied in a plastic form and which tends to harden under heat. The heating coil consists of a spiral of high resistance wire 23 such as is commonly used in electric heaters. This coil is partially embedded in the cement 27 which holds it in place. Two straps 26 are provided for clamping the asbestos cloth to pipe 29 and terminals 24 and 25 may be secured to these straps for terminating the ends of the heating coil as shown in Fig. 2.

The conductors 21 and 22 are connected with a source of electric supply. These are led into the heating coil through the pipe 14 where they connect to asbestos covered wires leading to the terminals 24 and 25. In pipe 29 and in that portion of pipe 14

subject to heat a filling 31 of mineral wool 55 is provided surrounding the conductors which holds them in place and absorbs vibration. Adjoining the mineral wool, a section of pipe 14 is filled with sealing wax as at 32, Fig. 2, this forms a long waterproof 60 seal for the outlet of the conductors. The outer end of the pipe 14 is filled with a cement 33 which hardens and forms a mechanical protection to the other fillings. The pipe 14 forms a convenient handle by 65 which the units may be carried even when they are heated.

When the chamber enclosed by pipe 11 is heated, the air and other gases in it are heated and expand, to permit these gases to 70 escape the safety valve 16 is provided. This consists of a plunger with a valve seat 42, Fig. 4, held closed by the spring 41. When the pressure under the valve overcomes the spring the gases escape through 75 the filter 43; this filter is provided to prevent dust from getting to the valve mechanism.

One use to which this invention is particularly adapted is for thawing switches 80 on a railroad track. For this purpose the units are placed below the rails 17 and 18 as shown in Figs. 5 and 6. In this position, vibration is excessive and the outer shell must be able to resist blows from falling 85 objects on passing trains. This construction is strong, comparatively light and the walls of the shell are thin to radiate the heat. The radiating surface is so designed with relation to the heating capacity that 90 while it will melt snow and ice, it will not boil water.

Having thus described my invention, I claim:

1. In an electric heater of the class described, in combination, a length of iron pipe of large diameter, reducing caps screwed to each end of said pipe, a length of pipe of small diameter screwed to one of said caps, a heating coil enclosed within said 95 large diameter pipe, conductors to said heating coil inserted within said small diameter pipe, and said latter pipe being filled with mineral wool where it is subject to heat, with a water-proof sealing compound adjacent to said mineral wool and with cement 100 at the outer end.

2. In an electric heater of the class de-

scribed, in combination, a length of pipe of
large diameter, reducing caps screwed to
each end of said pipe, an exterior length
of pipe of small diameter screwed to one
5 of said caps, an interior length of pipe of
small diameter extending between said caps,
a covering of asbestos cloth for said exterior
pipe, a covering of cement over said asbestos
cloth, a heating coil partially embedded in
10 said cement, and conductors for said heat-

ing coil led out through said exterior length
of pipe.

Signed at New York in the county of
New York and State of New York this
third day of March A. D. 1919.

EDWARD A. EVERETT.
